UNITED STATES PATENT OFFICE.

DANIEL J. SULLIVAN, OF KANSAS CITY, MISSOURI.

PAINT SPRAYER.

Application filed September 21, 1921. Serial No. 502,299.

To all whom it may concern:

Be it known that I, DANIEL J. SULLIVAN, a citizen of the United States, residing at Kansas City, in the county of Jackson and 5 State of Missouri, have invented a new and useful Paint Sprayer, of which the following is a specification.

My invention relates to paint sprayers and particularly to a device of this character 10 which employs compressed air to reduce liquid paint to a suitable spray for spraying upon the surfaces of wood and metal structures.

The object of the invention is to provide 15 a portable spraying device which may be connected with a supply of liquid paint under air pressure and also connected with a supply of compressed air and having self contained facilities for regulating the pressure 20 of the liquid paint and regulating the air pressure for reducing the liquid paint to a spray.

Another object of the invention is to provide 25 an inexpensive hand device of this character which may be manipulated by the operator at points remote from the paint supply.

Another object of the invention is to provide 30 a device of this character which is arranged to be self cleaning and having facility to prevent stoppage of the flow of liquid paint.

I attain these objects by means of the mechanism and combination of parts illustrated in the accompanying drawing in 35 which—Figure 1, is a side elevation of a paint sprayer embodying my invention; Figure 2, is a longitudinal section of the same, sectioning of the air valve and conduits being omitted; Figure 3, is an end view 40 of the same, and Figure 4, is an end view of the sprayer tube.

Similar numerals of reference refer to corresponding parts throughout the several 45 views.

The device comprises a hollow cylinder member 1, having internal screw threads at its forward end and external screw threads at its rearward end. On the upper side of 50 the member 1, is an integral boss 2, having a vertical bore which communicates with the interior of the cylinder member, thus forming an inlet port 3, for the liquid paint, the upper end of the boss has internal screw threads for receiving the screw end of a pipe section 4, the latter having internal screw

threads for receiving the screw end of a valve member 5, which is also provided at its upper end with screw threads for receiving the screw end of a pipe 6, which has 60 internal screw threads at its upper end for receiving the screw plug on a hose 7, which is connected between the pipe 6, and a supply of liquid paint under pressure, not shown. The valve member 5, is chambered 65 and divided by a diaphragm 8, having an orifice 9, which is adapted for receiving a needle valve 10, which operates to open and close the orifice 8, a wheel 11, being associated with the needle valve stem to facilitate the manipulation of the valve. The exterior of the member 1, is provided with an integral mass 12, having a horizontally extending boss 13, which is bored longitudinally to provide in the side of the member 1, 70 an inlet port 14, for the compressed air. The boss has internal screw threads for receiving the screw end of an elbow pipe 15, which also has internal screw threads for receiving the lower screw end of a valve 75 member 16, and a pipe 17, is screwed on the upper screw end of the valve member, the latter pipe is provided with internal screw threads for receiving the screw plug on a hose 18, which is connected between the pipe 80 mentioned and a supply of compressed air, not shown. The forward end of the member 1, is provided with a larger bore to provide an annular shoulder 19, to serve as a bearing for a peripheral flange 20, on the 85 inner end of a hollow cylindrical rotatable valve member 21, which operates in the member 1, to open and close the ports 3 and 14. The valve member 21, is arranged to project rearwardly outward of the member 90 1, and the projecting end thereof forms a handle portion 22, and the handle portion is scored to facilitate the manipulating the valve by hand. On the rearward end of the member 1, is screwed a stuffing box 23, having the usual packing ring to prevent leakage. A concentrically formed bearing block 95 24, is loosely mounted in the member 1, and has a stem 25, which is projected into the end of the valve member 21, thus bringing the block 24, to bear on the end of the valve member, the block has a bore at its horizontal axis to provide communication between the member 1, and the valve member 21. In the forward end of the member 1, is screwed 105 a plug 26, having a bore longitudinally thereof which communicates with the inte-

rior of the member 1, the plug is also provided with external screw threads for receiving a nozzle member 27, which is screwed therein, and the end of the nozzle is provided with a suitable mouth 28, for spraying and spreading the liquid paint which is forced through the nozzle. In the wall of the valve member 21, is a hole 29, which is adapted for registering with the inlet port 3, and, inwardly of the hole 29, at an angle of 90 degrees, is a hole 30, which is adapted for registry with the inlet port 14, at the moment the hole 29, obtains registry with the inlet port 3. To limit the rotative movement of the valve 21, the lower side of the wall of the member 21, is provided with a transverse slot 31, which is elongated to limit the rotative movements of the valve 21, to opening and closing the ports 3 and 14, whenever a stop 32, which is demountably secured in the wall of the member 1, is projected through the slot.

To operate the paint spraying device, the hole 7, is connected with the pipe 6, and with a tank, not shown, containing liquid paint under air pressure, and the hose 18, is connected with the pipe 17, and with a tank, not shown, containing a supply of compressed air. The hose mentioned may be of any suitable length to permit the use of the sprayer at any desired distance from the paint and air supply, thus tall buildings, bridges, and other structures may be painted with great economy.

When properly connected, the sprayer is operated by manipulating the needle valve 10, to allow the liquid paint to present itself at the inlet port 3, and the air valve 16, is manipulated to permit the compressed air to be present at the inlet port 14. The valve 21, is then rotated gradually to bring the holes 29 and 30, therein to register respectively with the ports 3 and 14, whereupon the liquid paint is forced into the valve member 21, and forced therefrom, through the reduced bore in the block 24, through the plug 26, and through the nozzle 27, by the air pressure admitted through the port 14, the paint spraying from the mouth 28, of the nozzle and spreading upon the material being painted. The spray may be reduced by rotating the valve 21, to partially open the ports 3 and 14, and the quantity of paint and pressure of air may be regulated by manipulating the needle valve and the air valve. In Figure 2, the holes 29 and 30, in the valve member 21, are shown fully registering respectively with ports 3 and 14. By removing the stop 32, from the slot 31, removing the plug 26, the block 24, and the

valve member 21, may be withdrawn from the member 1. This provision makes the parts accessible for repair or replacement.

Having described my invention what I claim is—

1. In a paint spraying device, the combination with a supply of liquid paint under pressure and a supply of compressed air, of a hollow cylinder member having an inlet port communicating with the supply of liquid paint under pressure and an inlet port communicating with the supply of compressed air, a hollow cylindrical valve member rotatably and demountably mounted in said hollow cylinder member and having in the wall thereof holes adapted for registering with the inlet ports in said hollow cylinder member, and a nozzle member mounted in the end of said hollow cylinder member and having an elongated opening in its end and forming a spreader.

2. In a paint sprayer, the combination with a supply of liquid paint under pressure and a supply of compressed air, of a hollow cylinder member having an inlet port communicating with the supply of liquid paint under pressure and an inlet port communicating with the supply of compressed air, a needle valve mounted on said hollow cylinder member and operating to open and close the communication between the hollow cylinder member and the supply of liquid paint under pressure, a valve member mounted on said hollow cylinder member and operating to open and close the communication between the hollow cylinder member and the supply of compressed air, a hollow cylindrical valve member rotatably and demountably mounted in said hollow cylinder member and operating therein to open and close communication between the valve member and the inlet ports in the hollow cylinder member, said valve member being arranged to project outwardly of the end of the hollow cylinder member to form of the projecting portion a handle for manipulating the valve by hand, a stop pin detachably mounted in the wall of said hollow cylinder member and piercing said hollow valve member and limiting the rotation thereof, and a nozzle member mounted in the end of said hollow cylinder member and having an elongated opening forming a spreader.

Kansas City, Missouri, September 15, 1921.

DANIEL J. SULLIVAN.
